(57) **CLAIM**

The ornamental design for a food cutting device, substantially as shown and described.

DESCRIPTION

FIG. 1 is an isometric view showing the front, top and right side of my design;

FIG. 2 is a front elevation view of my design;

FIG. 3 is a rear elevation view of my design;

FIG. 4 is an elevation view showing the left side of my design;

FIG. 5 is an elevation view showing the right side of my design;

FIG. 6 is a top plan view of my design;

FIG. 7 is a bottom plan view of my design; and,

FIG. 8 is an exploded view showing the front, top and right side of my design with removable parts and interchangeable blades.

The portions of the drawings shown in broken lines depict environment and do not constitute part of the claimed invention.

1 Claim, 8 Drawing Sheets(56)
